UNITED STATES PATENT OFFICE.

NILS D. LEVIN, OF COLUMBUS, OHIO.

MINE-PROTECTION SYSTEM.

1,234,185.

Specification of Letters Patent. Patented July 24, 1917.

Application filed May 14, 1912. Serial No. 697,352.

To all whom it may concern:

Be it known that I, NILS D. LEVIN, a citizen of the United States, residing at Columbus, in the county of Franklin and State of Ohio, am the inventor of certain new and useful Improvements in Mine-Protection Systems, of which the following is a specification.

My invention relates to mine protection systems and it has for its primary objects: the provision of an improved protection system adapted to protect and insure the safety of those in the mine and also to preserve the property in case of the occurrence of an explosion; the provision of improved safety mechanism automatically actuated by the action of an explosion; the provision of an improved system or arrangement of safety mechanism wherein any one or more units 15 may be automatically actuated by an explosion, and upon such actuation the remaining units actuated automatically. These together with such other objects as may hereinafter appear I attain by means of a construction illustrated in preferred form in 20 the accompanying drawings, wherein—

Figure 1 is a horizontal section through a mine entry showing a plan view of a unit of my improved safety mechanism; Fig. 2 is a longitudinal section through Fig. 1 showing a side elevation of the apparatus of Fig. 1; Fig. 3 is a partial section through the mechanism for operating the safety doors; and Fig. 4 is a side elevation of a detail of the 35 operating mechanism; Fig. 5 is a plan view of a modified form of the mechanism shown in Fig. 4; Figs. 6 and 7 disclose another form of closure mechanism; Fig. 6 being a section taken on the line VI—VI of Fig. 7, 40 and Fig. 7 an end view of Fig. 6; Fig. 8 is an end elevation of still another form of closure mechanism and Fig. 9 is a detail of the operating means employed in the mechanism shown in Fig. 8. Figs. 10 and 11 are 45 a plan and side view respectively of a form of closure mechanism of the same general type as that shown in Fig. 1; Fig. 12 is a longitudinal section through a modified form of closure or obstructing means; and 50 Figs. 13 and 14 are views of a detail of this form of mechanism; Fig. 15 is a diagram of the wiring of the system, and Fig. 16 is a section through a portion of a mine illustrating the general application of the entire 55 system. Fig. 17 is a diagram of another system of wiring; and Figs. 18 and 19 are

respectively a partial section and end elevation of a modification of the device of Fig. 12.

In mining operations and particularly in coal mining, the most damaging explosions are dust explosions. Explosions may start with gas but as a general rule the mine entries are ventilated and contain little or no gas, and an explosion therefore would not travel very far if it were not for the dust that feeds the flame. Experience has shown that during an explosion, there is a very strong current of air rushing in toward the explosion, this current being sufficient to throw a man down or lift him off the ground and carry him a distance toward the flame. Immediately following this inrush of air is an outrush of flame and hot gases, which results from the dust which is picked up by the inrushing air and is fed to the flame. Among the chief objects of my invention is the automatic prevention of the inrush of air above referred to, so that the explosion will lose in violence and soon die out, and the confinement of the gaseous vapors, commonly known as after-damp—which follow an explosion. My invention further contemplates the choking of the flames by means of dust or by the provision of non-combustible gases, the material from which they are formed being automatically carried to the point of explosion in a manner herein-after to be described.

Referring to Figs. 1 to 4 inclusive, it will be seen that in carrying out my invention, I provide a recess 3 in one of the walls of the entry 4 which is adapted to receive a sliding door 5 supported by rollers 6 from an overhead track 7 which extends from the inner end of the recess to the opposite wall of the entry and is mounted on the posts 8 and 9. The door is moved along the track in position to close the entry by means of a coil spring 10, one end of which is fastened to the door and the other end to a shaft 11 which is rotatably mounted in the door and carries a pinion 12 which engages a rack 13 supported from the track 7. The spring 10 is held in coiled position by means of mechanism to be described, and when released, rotates the pinion which moves along the rack 13 and drags the door with it. The mechanism for releasing the spring comprises a handle or arm 14 (see Fig. 3) the end of which is engaged by a trigger lever 15 which is pivotally mounted on the ful-

crum block 16 bolted to the supporting plate 17. The lever 15 is actuated by mechanism which I designate as a receiver and which comprises a shallow casing 18 fastened to 5 the support 17, a plate 19 movably mounted in the casing and a bellows 20 which serves to yieldingly hold the plate in position. The lever 15 is connected to the plate 19 by means of the link 21. When an explosion 10 occurs, the atmospheric pressure is at once greatly increased, and the plate 19 will be forced inwardly against the bellows and the outer end of the lever 15 moved clear of the arm 14 to release the spring 10. From the 15 foregoing, it will be apparent that the door will be automatically moved to closed position, upon the occurrence of an explosion.

My invention contemplates the provision of a plurality of safety closures or other 20 forms of obstructing devices which are arranged at various places through the mine entries and which are electrically operated in such manner that upon the automatic actuation of any mechanism located near the 25 point of an explosion, all of the safety devices will be actuated throughout the mine. To this end, in addition to the automatic receiver mechanism already described, I provide for each safety device a solenoid 22 30 or equivalent electromagnetic mechanism, which is connected to the lever 15 at 23. The various solenoids are preferably connected in multiple, the diagrams in Figs. 15 and 17 showing two systems of such wiring, 35 and each lever 15 carries at its outer end switch contact bars 24 which make contact with the terminals 25. The closure of any one of these switches closes the circuit for all the solenoids and upon the actuation of 40 any one of the receiver mechanisms the circuit will be closed and all the solenoids actuated to release the operating mechanism for the various doors and the like. By thus closing off the various entries the inward 45 rush of air is prevented with the result that no dust is fed to the flame. In some cases it is probable that the doors immediately adjacent the point of explosion may not have time to close before the back rush of air, but they will always close in sufficient 50 time to prevent the after-damp from circulating through the mine. The other doors will be closed in sufficient time however.

In Fig. 5, I have illustrated a slightly 55 different form of receiver adapted more particularly for use in a system where the safety devices are actuated by electricity solely. In this arrangement, I provide a cylinder 26 secured to the support 17 and provided 60 with a piston 27 which is adapted to be moved by change of atmospheric pressure as hereinbefore described. The stem 27^a of the piston 27 carries an insulating block 28 to which are secured the contact blocks 24 65 adapted to contact with the terminals 25.

The closure of any of these switches will operate all of the solenoids which actuate the safety devices.

In Figs. 6 and 7 I have illustrated a modified form of closure device which comprises a sheet 29 of material of sufficient strength 70 rolled about an upright roller 30 mounted in the supporting beams of the mine to one side of the entry. The sheet is drawn across the entry by means of a cable 31 which passes around a second roller 32, over the pulley 33 and the large drum 34. The large drum is operated by means of a fluid pressure piston 35, the stem 35^a of which is connected to a cable 36 which passes around 75 a small drum 37 bolted to the large drum. This arrangement of drums multiplies the stroke of the piston sufficiently for the purposes required. The admission of fluid pressure to the cylinder is controlled by the 80 valve 38 which is preferably operated by a solenoid 22 in the same manner as previously described.

In Fig. 8 I have illustrated an arrangement similar to that of Fig. 6. This device 85 comprises a strip 29 of suitable material which is rolled about a horizontally disposed roller 39 and is provided at its lower end with a weighted member 40 recessed at 41 so that it will drop below the tracks 42 and 90 completely close the entry. The roller shaft is provided with a ratchet wheel 43 which is engaged by a pawl 44 which is preferably operated by a solenoid 22, as before, but which may also be actuated manually by 95 means of the handle 44'. In this construction, when the pawl is released the weight 40 draws the strip 29 downward and closes the entry.

In Figs. 10 and 11 I have illustrated a 100 door closure composed of two door members 45 and 45^a which are mounted in opposing recesses cut in the walls of the entry and are drawn together to close the entry by means of the weight 46, the cable 47 and the pulleys 48, 49 and 50. An end of the cable is fastened to each door. The counterbalance weight 46 is released by a trip mechanism comprising a trip plate 51 pivotally supported on a platform 52 and a trigger 53 engaging the end of the trip plate. The trigger is operated by a solenoid 22 or any other forms of operating mechanism described. 110

In Fig. 12 a modified form of obstructing means is shown. My invention also contemplates the obstruction or filling of the entries with non-combustible gases which will choke the flames of explosion, and to this end I provide a receptacle 53 secured to the roof of the entry, the bottom 54 being hinged at one end. The bottom 54 is held in closed position by means of a trigger 55 which is operated preferably by a solenoid 22 or other suitable mechanism such as described. The inner side wall of the receptacle is hinged 125 130

to the bottom plate 54 at 53' so that when the trigger is released the receptacle will be immediately emptied. The receptacle is filled with stone dust, marble dust, and other 5 like material, which may, if desired, be of such chemical composition that when brought into contact with heat it will generate carbon-dioxide or other non-combustible gas which chokes out the flames of the explosion or fires resulting therefrom. I prefer not to rely solely on the formation of gases, however, and provide dust in sufficient quantities to choke the flames by its volume. The dust is maintained in dry condition by means 10 of the electric heater 54'. A number of receptacles are located at various points throughout the entries and when emptied automatically on the occurrence of an explosion, the back rush of air carries the stone 15 dust to the point of explosion and thus practically forms a wall or obstruction to the advance of the flames and the spread of the explosion. This form of safety obstruction may be used in place of the safety door constructions 20 already described, but is preferably used in conjunction therewith as will presently appear. Another form of automatic receiver mechanism is shown in section in Fig. 13. This form of mechanism is 25 particularly adapted in a system where the safety mechanism is operated solely by electricity, and it comprises a suitable casing 30 55 in which is mounted a fixed insulation block 56 and a movable insulation block 57, the two blocks being normally held apart 35 by means of the springs 58. Switch contact blocks 59 and 60 are adapted to make contact and close the electrical circuit when the insulating block 57 is moved inwardly 40 by the action of an explosion. The block 57 is held in position in the casing 55 by means of the rod 61. Fig. 14 is an end view of the device of Fig. 13. Fig. 15 is a diagrammatic illustration of the preferred wiring 45 of the system. The positive wire is indicated by the numeral 62, the negative wire by 63, the electro-magnetic members by 64 and the receiving mechanisms and switches by 65. In Fig. 17 I have shown the electro- 50 magnetic members connected in multiple, both the positive and the negative sides of the circuit being broken.

Referring now to Fig. 16, it will be seen 55 that the general application of my invention to a mine is illustrated. As therein indicated, the main entries are preferably provided with a plurality of the receptacles 53, the electro-magnetic operating means therefore being connected electrically. The butt 60 entries 4 are preferably provided with door closures 5, such for example as those shown in Figs. 1 and 2. The workings from the butt entries are provided with manually operated doors 66, with air pipes 67 and telephones 68. Each working may also be pro-

vided with a receiver mechanism 65 adapted to actuate the safety devices throughout the mine. The receiving mechanisms for emptying the receptacles 53 are mounted in the supporting piles 69 in the main entries. 70

In Figs. 18 and 19 I have illustrated a modification of the device of Fig. 12. In this construction the receptacle 53 is provided with a hinged bottom plate 54, having the end wall of the receptacle hinged thereto at 53', the contents being kept in dry condition by an electric coil or heating member 54', as before described. The bottom plate is held in closed position by means of the vanes 70 and 71 which are pivotally suspended from the support 72 adjacent the outer end of the plate 54 in such manner that the bar 73 which is fastened on the bottom plate rests on the upper edges of the vanes as indicated at 74. A draft of air in 80 either direction from an explosion moves the vanes as indicated in dotted lines and releases the bar 73 upon which the bottom plate drops inwardly discharging the contents of the receptacle. 90

From the foregoing description it will be apparent that upon an explosion in any part of the workings, all parts of the mine are effectually shut off by automatic means, the inrush or back rush of air carrying with it 95 the coal dust is prevented, as well as the spread of after damp, and in case the explosion should occur in a main entry the progress of the flames is obstructed by the presence of dust which is automatically carried to the point of explosion. The advantages of the mechanism will be readily apparent. 100

Having thus described my invention and 105 illustrated its use, what I claim as new and desire to secure by Letters Patent is the following:

1. A mine closure device comprising in combination, a driving member for moving the closure device to closed position, locking means for normally holding said driving member against movement, a lever having operative relation with said locking means, a lever-operating means, an electric circuit, and a switch operated by said lever to close 110 said electric circuit when the lever is operated to disengage the locking means from the driving member. 115

2. In safety equipment for mines, a mine closure device releasably maintained in position, a lever for releasing the said closure, operating means for the lever, an electric circuit, a switch for closing said circuit carried by the lever and closed when the lever is operated to release the said closure. 120

3. In safety equipment for mines, a plurality of electrically connected mine closures releasably maintained in position, an operating lever for each of said closures, a pressure diaphragm for moving the lever to re- 125 130

lease the mine closure, a solenoid for moving said lever, to release the mine closure, the diaphragm and the solenoid being mounted so that each may operate the lever independently of the other.

4. In safety equipment for mines, a plurality of mine closures releasably maintained in position, an operating lever for each of said closures, a pressure diaphragm and a 10 solenoid operatively connected to each of said levers, all of said solenoids being electrically connected one to the other, electrical contacts on each of said levers whereby when any one lever is moved by its diaphragm to release one of said closures the electrical contacts complete the circuit between the solenoids and cause each of the other levers to be actuated by its solenoid.

5. In safety equipment for mines, a plurality of mine closures releasably maintained in position, a pressure diaphragm for each closure, a solenoid for each closure electrically connected one to the other in multiple, a switch at each closure, release means for 20 each closure, and means whereby the movement of a pressure diaphragm operates said release means and closes the adjoining

switch, completing the circuit of the solenoids.

6. In safety equipment for mines, a mine 30 closure device releasably maintained in position, a pressure operated member for each closure, means releasably maintaining the closure in position, an electric circuit and a switch for closing said circuit, and operative connections between said pressure operated member and said release means and said switch.

7. In safety equipment for mines, a barrier adapted for automatic movement, releasable locking means adapted to lock the barrier against movement, electromagnetic actuating means and atmospheric pressure actuating means, the said releasable locking means being subject to actuation by both of 40 said actuating means.

In testimony whereof I have hereunto signed my name in the presence of the two subscribed witnesses.

NILS D. LEVIN.
